I. J. OWEN,
SUCTION CLEANER,
APPLICATION FILED MAY 6, 1920.

1,404,889.

Patented Jan. 31, 1922.

UNITED STATES PATENT OFFICE.

IRA J. OWEN, OF GRAND RAPIDS, MICHIGAN, ASSIGNOR TO BISSELL CARPET SWEEPER COMPANY, OF GRAND RAPIDS, MICHIGAN.

SUCTION CLEANER.

1,404,889.

Specification of Letters Patent. Patented Jan. 31, 1922.

Application filed May 6, 1920. Serial No. 379,284.

To all whom it may concern:

Be it known that I, IRA J. OWEN, a citizen of the United States, residing at the city of Grand Rapids, county of Kent, State of Michigan, have invented certain new and useful Improvements in Suction Cleaners, of which the following is a specification.

This invention relates to improvements in suction cleaners. The invention relates particularly to the nozzle portion and the conduit and connections therefrom to the suction fan.

The object of the invention is to facilitate the flow or inrush of air into the nozzle and to facilitate the passage of the same to the fan or dust collector.

Objects of the invention pertaining to details and economies of construction and operation will definitely appear from the detailed description to follow. I accomplish the objects of my invention by the devices and means described in the following specification. The invention is clearly defined and pointed out in the claims.

25 A structure which is a preferred embodiment of my invention is clearly illustrated in the accompanying drawing, forming a part of this specification, in which:

Fig. I is a perspective view of my improved nozzle structure in connection with the suction fan of a suction cleaner, other parts being broken away.

Fig. II is a front elevation view of the structure appearing in Fig. I.

35 Fig. III is a detail side elevation view of the structure.

Fig. IV is an enlarged detail vertical elevation view, partially in section on line 4—4 of Figs. II and V.

40 Fig. V is a reduced vertical detail sectional elevation view taken on line 5—5 of Fig. IV.

Fig. VI is an enlarged detail sectional elevation view of the end opening in the nozzle taken on line 6—6 of Fig. III.

In the drawing all the sectional views are taken looking in the direction of the little arrows at the ends of the section lines, and similar reference characters refer to similar parts throughout the several views.

Considering the numbered parts of the drawing, 1 is the nozzle structure generally secured to the side of the suction fan case 2 which delivers into the dust collector bag or other device 3, seen in Fig. I. The nozzle is

built out into a broad intake portion 4 at the bottom, the front and rear walls tapering slightly into the same, (see Fig. IV). The air passage 5 extends upwardly at 6 where it connects to the fan and has a notched opening 7 at each end rounded externally to facilitate the entry of air and restricted at 8 a little distance within the outer margin to secure Venturi tube action. The intake at the end is rounded as shown.

60 This Venturi action is also secured in the main part by the contracted neck 9 in the main passage 5 leading upwardly to the fan. This is made within the nozzle part and the walls are curved and rounded as shown to 70 minimize the friction.

This nozzle portion is made up of a main block 8 which is tapered downwardly as seen in Fig. IV, and provided with a front plate 10. A flange 11 is provided for securing it to the fan case 2 or front of the vacuum cleaner.

75 I have described my improvement as particularly applied to suction cleaners having a horizontal motor and fan. It is very effective for these because all of the dust and debris collected must be carried up a considerable distance from the floor and this device does the same very effectively.

Also, by the Venturi form of the outer 8 end of the nozzle, a strong current of air enters the nozzle mouth at each end and sweeps across a comparatively narrow section of the carpet embraced within the nozzle, the nozzle opening between the front and rear walls being about one-half inch wide. This construction at each end of the nozzle is of the highest advantage because so strong a current of air is created that it readily collects dust and loose particles from corners of the floor next the baseboard. Also, the structure cleans a swath, so to speak, considerably wider than the nozzle when it is in use.

80 The entry of a strong current of air at the end is of very highest consequence because it at once collects and forcibly carries away any dust that is disturbed by the comparatively small circulation of air under the front and rear edges of the nozzle, greatly facilitating the action of the nozzle and collects all dust and lint from any carpet, or even from a bare floor. The nozzle is adjusted in use three thirty-seconds of an inch or more above the surface to be cleaned. The Venturi action

therefore insures effect to the suction or in-rush of air for the entire width of the nozzle.

I have described my improved nozzle structure for suction cleaners in its most approved form. I desire to claim the same specifically as here illustrated and also to claim the same broadly. I have shown a specific form of a nozzle especially adapted for use upon hand operated vacuum cleaners in the application filed concurrently herewith. The form here shown is especially adapted for power cleaners.

Having thus described my invention, what I claim as new and desire to secure by Letters Patent is:

1. A nozzle structure for suction cleaners having a broad intake mouth with notched openings at the end, curved exteriorly and having a contracted portion at a little distance from the end to secure Venturi tube action, the main passage being also contracted intermediately and having an expanded discharge portion to secure Venturi tube action, the contracted walls of said passage being on curved lines, as specified.

2. A nozzle structure for suction cleaners having a broad intake mouth with notched

openings at the end, the main passage being contracted intermediately and having an expanded discharge portion to secure Venturi tube action, the contracted walls of said passage being on curved lines and the front and rear walls being tapered to the intake, as specified.

3. A nozzle structure for suction cleaners having a broad intake mouth with notched openings at the end, the main passage being contracted intermediately and having an expanded discharge portion to secure Venturi tube action; the contracted walls of said passage being on curved lines, as specified.

4. A nozzle structure for suction cleaners having a broad intake mouth with notched openings at the end, curved exteriorly and having a contracted portion at a little distance from the end to secure Venturi tube action, as specified.

In witness whereof, I have hereunto set my hand and seal in the presence of two witnesses.

IRA J. OWEN. [L. S.]
